EXAMINATION LIGHT

Ronald K. Meyer, 25 Janes St., Mill Valley, Calif.

Filed July 2, 1963, Ser. No. 75,634

Term of patent 14 years

(Cl. D48—20)

FIG-1

FIG-2

FIG-3

FIG-4

FIG-5

FIG. 6

FIG. 1 is a front plan view of the examination light embodying my new design;

FIG. 2 is a side elevation view of the examination light;

FIG. 3 is a rear plan view of the examination light;

FIG. 4 is a front elevation thereof with portions shown broken away to clarify details on the interior portion of the head; and

FIG. 5 is an elevation view of the light as seen from the right of FIG. 2.

FIG. 6 is a side perspective view of the examination light.

I claim:

The ornamental design for an examination light, as shown.
